VACUUM BOTTLE

Robert O. Burton, 441 St. James St., Chicago, Ill.

Filed Dec. 30, 1959, Ser. No. 58,857

Term of patent 14 years

(Cl. D58—11)

FIG. 1.

FIG. 2.

Fig. 1 is a side elevational view of a vacuum bottle showing my new design, and

Fig. 2 is a top plan view thereof.

The side not shown is the same as the side shown.

I claim:

The ornamental design for a vacuum bottle, as shown and described.
